UNITED STATES PATENT OFFICE.

ORMOND M. LISSAK, OF WESTPOINT, NEW YORK.

CARTRIDGE-CLIP.

No. 810,161

Specification of Letters Patent.

Patented Jan. 16, 1906

Application filed February 11, 1905. Serial No. 245,192.

To all whom it may concern:

Be it known that I, ORMOND M. LISSAK, a citizen of the United States, residing at Westpoint, county of Orange, and State of New York, have invented a new and useful Improvement in Cartridge-Clips, of which the following is a full, clear, and exact description, reference being had to the accompanying drawings, which form a part of this specification.

My invention has for its object an improvement in the construction of cartridge-clips whereby in transportation and use the cartridges are firmly held in the clip and yet the locking means may readily be disrupted when the cartridges are to be removed from the clip.

I will first describe the embodiment of my invention illustrated in the accompanying drawings and then point out the invention in the claims.

In the drawings, Figure 1 is a perspective view of the cartridge-clip. Fig. 2 is an elevation of the clip with cartridges assembled therein. Fig. 3 is an elevation of the clip with cartridges assembled therein and showing the tongues crimped into the cartridge-groove.

The clip (shown in Fig. 1) consists of the body A, having the projecting internal flanges a a and the rounded ends a' a'. Within the body is the spring B, made of soft metal and having the rounded ends b, from which project the tongues b'. The cartridges C, Figs. 2 and 3, have the groove C' and heads c. The cartridges are inserted in the clip so that the flanges a a rest in the grooves C', and the outer surface of the heads rest against the spring B. This is the condition shown in Fig. 2. The tongues b' are then bent into the grooves in the outer cartridges. This is the condition shown in Fig. 3 and the final condition.

The spring is of soft metal and the tongues of such width that when folded around the head of the cartridges in the clip they may be readily bent back by pressure of the thumb upon the uppermost cartridge and of such length that the end of the tongue can be crimped into the groove of the cartridge-head. The tongues hold the cartridges securely in the clip, but permit their easy ejec-

tion when desired, while the crimping of the ends into the groove of the cartridge prevents accidental catching and bending back 55 of the tongues by a part of the user's clothing or the soldier's equipment. It also prevents scratching of the user's hands in ejecting the cartridge from the clip.

The use of the tongue permits the rounding 60 of the clip ends, which is an advantage, as the corners of the square-ended clip wear the pockets of the user's cartridge-belt. Without the tongues a rounded clip of this pattern cannot be used, as the ends of the 65 cartridges are held so near the end of the clip that with the slightest movement they would fall out. By making the spring of soft metal the tongue will not break off when bent back.

Having now fully described my invention, 70 what I claim, and desire to protect by Letters Patent, is—

1. A cartridge-clip, comprising a body and inserted spring and a flexible tongue projecting at each end thereof adapted to be bent 75 into a groove in the cartridge-head.

2. In combination, a cartridge-clip, comprising a body and inserted spring, and a flexible tongue projecting at each end thereof, a plurality of cartridges, having grooved 80 heads, in said clip, the tongues being bent into a groove in the head of the cartridge.

3. A cartridge-clip comprising a body and inserted spring, a tongue, projecting from each end of said spring; adapted to be bent 85 into a groove in the cartridge-head.

4. A cartridge-clip comprising a body and inserted spring, and a tongue of flexible material, projecting from each end of said spring, adapted to be bent into a groove in the car- 90 ridge-head.

5. A cartridge-clip comprising a body and a soft-metal inserted spring, and a tongue of flexible material, projecting from each end of the spring, adapted to be bent into a groove 95 in the cartridge-head.

6. A cartridge-clip comprising a body and inserted spring, the end of the body and spring being rounded.

7. A cartridge-clip comprising a body and inserted spring, the ends of the body being rounded, and a projecting tongue of flexible material at each end of the clip. 100

8. A cartridge-clip comprising a body and

inserted spring, the ends of the spring being rounded, and a projecting tongue of flexible material at each end of the spring.

9. A cartridge-clip comprising a body and inserted spring, the end of the body and spring being rounded, and a projecting tongue of flexible material at each end of the clip.

10. In combination, a clip having a body portion and inserted spring and projecting tongues, of a plurality of cartridges having

grooved heads inserted therein, each tongue being bent into the groove of the cartridge-head adjacent thereto.

In testimony of which invention I have hereunto set my hand, at Westpoint, New York, on this 3d day of February, 1905.

ORMOND M. LISSAK.
